LIQUID DISPENSING DEVICE

Herbert L. Magill, Chicago, Ill.

Application December 16, 1935, Serial No. 54,614

10 Claims. (Cl. 225—22)

This invention relates to a mechanism for dispensing liquids from containers such as bottles, by means of air pressure produced by the mechanism. It is particularly adapted for dispensing beverages from bottles, especially "carbonated" beverages which are charged with a gas which would rapidly escape if the bottle or container were completely uncovered and the beverage merely poured therefrom. An object of the invention is to provide a mechanism which may be readily fitted into the neck of a bottle, and which shall be of slight proportions and of convenient design for manipulation. Another object is to provide a mechanism which can be economically manufactured, and which is adapted to fit bottles of different dimensions. The invention consists in various features and elements of construction in combination, as herein shown and described and as indicated by the claims.

In the drawing:

Figure 1 is a vertical axial section of a bottle and a device embodying this invention fitted thereto.

Figure 2 is a fragmentary elevation largely in section, as indicated by the line 2—2 on Figure 1.

Figure 3 is a transverse detail section taken as indicated at line 3—3 on Figure 2.

Figure 4 is a transverse section taken as indicated at line 4—4 on Figure 2.

In the drawing a typical beverage bottle is shown in section at 1, with the mechanism embodying my invention secured in the neck, 2, of the bottle. The device includes a pump cylinder,

3, in which a piston, 4, is mounted for reciprocation with its hollow stem, 5, extending through an opening in the head or top wall, 6, of the cylinder. The cylinder proper may be formed as a die casting with its side walls unitary with the bottom wall, 7, and with a guide post or stud, 8, upstanding from said bottom wall for centering and steadyng a coil spring, 9, which urges the piston yieldingly toward the upper limit of its stroke. Extending downwardly from the bottom wall, 7, is a unitary stem, 10, threaded at 11 to receive an adjusting nut, 12, and threaded at 13 adjacent its lower end to receive a terminal fitting, 14. A plug, 15, of flexible material, such as rubber, is fitted over the portion of the stem just below the threads, 11, so as to fit between the stem and the opening in the neck, 2, of the bottle, 1, in which the device is to be mounted. A washer, 16, is interposed between the upper end of the fitting, 14, and the lower end of the plug, 15; and a washer, 17, is interposed between the

nut 12, and the upper end of the plug, 15. The terminal fitting, 14, is screwed onto the threads, 13, and remains fixed in position, but the nut, 12, is adjusted on the threads, 11, to compress the plug, 15, longitudinally or axially so as to cause to expand radially or laterally to fit more tightly into the neck, 2, of the bottle. This serves to seal the device in place so that any air pressure produced in the bottle will be held against leakage.

The hollow stem, 5, of the piston includes an annular shoulder, 18, against which the upper end of the spring, 9, reacts, and includes also a bridge, 19, which provides a stop for a spring, 20, associated with a check valve, 21, which seats upwardly over a port, 22, in the cap, 23, of the stem. Inlet ports, 24, lead radially from the side walls of the cap, 23, to its port, 22, and on the upstroke of the piston air is admitted past the check valve, 21, for filling the cylinder, 3. When the piston, 4, is forced downwardly, this air in the cylinder is driven through an outlet port, 25, in the bottom wall, 7, past a check valve, 26, whose spring, 27, holds it normally seated. The port, 25, leads to a passage, 28, in the stem, 10, and this passage opens laterally at 29 into an annular recess, 30, in the terminal fitting, 14. Several ports, 31, lead outwardly from the annular passage, 30, to the interior of the bottle, 1. Thus the air forced from the cylinder, 3, by the downward movement of the piston, 4, is transferred under pressure into the upper portion of the bottle, thus placing the liquid contents under pressure.

The fitting, 14, serves as a coupling between the lower end of the stem, 10, and a tube, 32, which extends downwardly into the bottle. However, to provide for bottles of various depths I prefer to add a telescoping terminal section, 33, to the tube, 32, and to ensure a leak-proof connection between the two sections by expanding the lower end of the tube, 32, at 34 to contain a quantity of soft packing, 35, and a threaded gland or packing nut, 36, as seen in Figure 1. The extreme lower end of the tube, 33, may be notched, 37, as seen at 37, to ensure that when it strikes the bottom of the bottle it will not be sealed against the bottom wall—the notches, 37, serving as inlet ports for the liquid which will be forced up the tube, 33, and tube, 32, and also up into the passage, 38, of the stem, 10, when the air pressure is applied to the upper surface of the liquid in the bottle, 1, by means of the pump, as already described.

The liquid being thus under pressure and fill-

ing the outlet tube, 33, 32, 38, is ready to be discharged at will. Such discharge is controlled by means of a valve, 40, of tapered form, whose seat, 41, forms a portion of a transversely disposed passage, 42, in the bottom wall, 7, of the pump cylinder casting. The valve, 40, has a stem, 43, terminating in a head or button, 44, and extending through a quantity of packing, 45, which is held in position in a recess or pocket, 46, cored 10 in the bottom wall, 7, of the cylinder casting. A spring, 47, reacts between the head or button, 44, and a washer, 48, overlying the packing, 45, and thus serves to hold the valve, 40, normally closed. The operating button, 44, is thus conveniently 15 located so that when the neck, 2, of the bottle is grasped in the hand the thumb may be applied to the button, 44, so that a slight pressure thereon will open the valve, 40, permitting the liquid to flow from the passage, 38, into the passage, 42, and through the discharge spout, 48, which is 20 screwed into the threaded end of the passage, 42, as seen in Figure 1.

A piston, 4, is shown as consisting of a pair of cup washers, 50, clamped between washers, 51 and 25 52, by rivets, 53, and this assembly is secured to the lower end of the hollow stem, 5, by a hollow plug, 54, having a head, 55, which may be of octagonal form, as shown in Figure 3. The hollow stem, 5, is anchored against rotation by engagement 30 of an upturned lug, 51a, on the washer, 51, with a notch, 51b, in the lower end of said hollow stem. Just under the head, and gripped between it and the washer, 52, I interpose a sheet metal member, 56, having an arm, 57, secured under the 35 head of one of the rivets, 53, and having outwardly extending lugs, 58, disposed at such angles to each other that one of them may be aligned with one of the sides of the octagonal head, 55, when the latter is adjusted to its final position. 40 As seen in Figure 3 this lug may then be bent against the flat side of the head, 55, serving as a nut lock to retain it. Another arm, 59, of the member, 56, is offset below the washer, 52, in spaced relation thereto and formed so that it can 45 engage under the head, 60, of a screw set into the upper surface of the bottom wall, 7, of the cylinder. Thus, when the pump is not in use, the piston may be forced to the lower limit of its stroke and rotated until this lug, 59, hooks under the 50 screw head, 60, so as to retain the piston in this position against the force of its spring, 9, thus rendering the device somewhat more compact and 55 slightly with the cap, 23, of the piston stem disposed close to the head, 6, of the cylinder.

55 As a matter of design, Figure 3 indicates that a portion of the post, 8, is cut away so that its external form is not truly cylindrical. This merely results from the fact that the chamber for the valve, 26, is so located that its circular outline 60 would overlap that of the post, 8, and a portion of the post is omitted to permit withdrawing the core for this valve chamber in making the cylinder casting. As seen in Figure 4, the stem, 10, is cored to contain both the air inlet passage, 28, 65 and the discharge passage, 38, for the liquid, and the external form of this stem is approximately square with rounded corners, so that when the rubber plug, 15, is compressed around it, the square form of the stem will tend to hold the 70 entire fixture against rotation in the neck of the bottle more firmly than it would be held by friction alone.

75 It will be seen that the device as described is compact and simple to apply to any standard bottle, and that it will be applicable to a con-

siderable range of sizes of bottle necks by virtue of the adjustability of the soft rubber plug, 15. For fitting the device to a still wider range of sizes one or more substitute rubber plugs of different diameters may be supplied as a part of the outfit, 5 10 if desired. The principal element comprising the pump cylinder, 3, and the stem, 10, being designed for manufacture as a die casting, may be produced economically, and the additional parts may be readily assembled without any extensive machining or fitting. While there is shown and described herein certain specific structure embodying the invention, it will be manifest to those skilled in the art that various modifications and re-arrangements of the parts may be made without departing from the spirit and the scope of the invention, and that the same is not limited to the particular form herein shown and described, except in so far as indicated by the appended claims. 15 20

I claim:

1. A liquid dispensing device comprising a cylinder having a bottom wall with a guide post upstanding therefrom, a piston in the cylinder and a hollow stem for the piston telescopically movable 25 over said post with a spring coiled about the post and within said stem normally urging the piston away from said bottom wall, an inlet port in said stem, a check valve for said port opening inwardly, said bottom wall having a discharge port with 30 a check valve therefor opening outwardly, said stem having an outlet passage communicating with said discharge port, and means for securing the stem sealably in the neck of a bottle or other container. 35

2. A liquid dispensing device comprising an air pump including a cylinder having a bottom wall with a stem extending rigidly downward therefrom, a piston in the cylinder, an operating stem for the piston extending upwardly through the 40 top of the cylinder, a spring normally urging said piston to its upper limit, said bottom wall having an outlet port and the stem having a passage communicating therewith, means for sealably securing the stem in the neck of a bottle or other 45 container with said outlet passage opening into the cavity of the container, a check valve for the outlet port in the bottom wall of the pump cylinder, said stem having a second passage and a conduit communicating therewith adapted to extend substantially to the bottom of the container, 50 an outlet for said second passage being formed in the bottom wall of the cylinder and a discharge spout for said outlet.

3. In the combination defined in claim 2, said 55 conduit including a telescoping section for adjusting its length to the depth of the container and having a lateral opening at its lower end to admit liquid from the container.

4. In the combination defined in claim 2, said 60 outlet in the bottom wall of the cylinder being formed as a transverse passage including a conical portion which intersects the communicating passage of the stem and a conical valve seating therein to control the outlet with the stem for 65 said valve, and a head on said stem projecting laterally from the cylinder, together with spring means normally holding the valve in closed position.

5. In the combination defined in claim 2, said 70 stem having a threaded portion adjacent the bottom wall of the cylinder, a plug of elastic material encompassing the stem below said threaded portion, a nut on said threaded portion, a washer interposed between said nut and the plug, and 75

means providing a shoulder on the stem at the opposite end of the plug whereby adjustment of the nut will compress the plug longitudinally and expand it laterally for sealably securing the device in position.

6. In the combination defined in claim 2, said stem being of non-circular cross-section, a plug of elastic material fitted onto the stem, and means associated with the stem and adjustable thereon for compressing said plug longitudinally to expand it laterally for sealably mounting the device in position.

7. A liquid dispensing device comprising an air pump including a cylinder having a bottom wall with means associated therewith for securing the cylinder to the neck of a bottle or other container, a piston in the cylinder, an operating stem for the piston extending upwardly through the top of the cylinder, a spring normally urging said piston to its upper limit, a headed stud upstanding from the bottom wall, and a lug offset from the under side of the piston disposed to engage under the head of said stud when the piston is depressed to its lower limit and rotated for effecting such movement.

8. A liquid dispensing device comprising a cylinder having a bottom wall and means for securing it sealably to the neck of a bottle or other container, a piston in said cylinder, a head for the cylinder having a central opening, a stem for the piston extending through said opening and comprising a hollow member extending through the piston, said stem having an annular shoulder, a coil spring seated against said shoulder and extending downwardly within the hollow stem to the bottom wall of the cylinder and stressed to urge said piston to the upper limit of its stroke, a bridge in said hollow stem above said spring, a cap for said stem having laterally opening inlet ducts, a port in the cap through which said ducts communicate with the interior of the stem, a check valve controlling said port and a spring for said valve reacting against said bridge, the bottom wall of the cylinder having a discharge port arranged to communicate with the interior of the container on which the device is mounted.

9. A liquid dispensing device comprising an air pump including a cylinder having a bottom wall with a stem extending rigidly downward therefrom and means for sealably securing said stem in the neck of a bottle or other container, a piston in the cylinder formed with a central opening, a stem for the piston comprising a sleeve extending from the upper side of the piston and a headed sleeve extending through the piston and threaded to the first mentioned sleeve for clamping engagement with the piston, a spring seated on the bottom wall and extending into said sleeves for yieldingly urging the piston to its upper limit, and a lock washer secured under the head of the second mentioned sleeve and independently anchored to the piston, said washer having a lug adapted to be bent into engagement with a non-circular portion of the head of said sleeve to lock it against rotation and having a second lug offset in a plane below the piston, together with shouldered means spaced slightly above the bottom wall of the cylinder and positioned so that said offset lug will engage under the shoulder thereof for holding the piston at its lower limit when the piston is depressed and rotated for such engagement.

10. A liquid dispensing device comprising an air pump including a cylinder having a bottom wall with a stem extending rigidly downward therefrom, a piston in the cylinder, an operating stem for the piston extending upwardly through the top of the cylinder, said bottom wall having an outlet port and the stem having a passage communicating therewith, means for sealably securing the stem in the neck of a bottle or other container with said outlet passage opening into the cavity of the container, a check valve for the outlet port in the bottom wall of the pump cylinder, said stem having a second passage and a conduit communicating therewith adapted to extend substantially to the bottom of the container, an outlet for said second passage being formed in the bottom wall of the cylinder, and a discharge spout for said outlet.
